United States Patent Office

Des. 192,404
Patented Mar. 13, 1962

192,404

AQUARIUM

Norman D. Moore, R.R. 1, Box 86, Ludlow Falls, Ohio

Filed Nov. 28, 1961, Ser. No. 67,726

Term of patent 14 years

(Cl. D91—2)

FIG-1

FIG-2

FIG-3

FIG-4

FIG-5

FIGURE 1 is a perspective view of an aquarium showing my new design.

FIGURE 2 is a front elevational view.

FIGURE 3 is a sectional view taken substantially on line 3—3 of FIGURE 2.

FIGURE 4 is an end elevational view;

FIGURE 5 is a bottom plan view.

I claim:

The ornamental design for an aquarium, substantially as shown.
